UNITED STATES PATENT OFFICE.

HORACE W. CLARK, OF MATTOON, ILLINOIS.

WELL ATTACHMENT.

SPECIFICATION forming part of Letters Patent No. 772,692, dated October 18, 1904.

Application filed February 25, 1904. Serial No. 195,303. (No model.)

To all whom it may concern:

Be it known that I, HORACE W. CLARK, a citizen of the United States, and a resident of Mattoon, in the county of Coles and State of Illinois, have invented a new and Improved Well Attachment, of which the following is a full, clear, and exact description.

My invention relates to attachments for wells; and its principal objects are to provide means for increasing the efficiency of the associated pumping mechanism and for the cleaning of the well-casing.

It consists in the various features and combinations hereinafter described, and more particularly claimed.

Reference is to be had to the accompanying drawings, forming a part of this specification, in which similar characters of reference indicate corresponding parts in both figures.

Figure 1 is a view of the upper portion of a well and pump embodying one form of my invention, part being in perspective and part in vertical section; and Fig. 2 is a vertical section through the lower portion of the well-casing.

H designates the well proper or casing, to the lower end of which is attached a perforated strainer H', connected to the casing by a ring p, preferably of lead. The lower end 30 of the strainer may be closed by the cap L. Into the casing from the upper end extends the suction-pipe G, reaching nearly to the lower end of the strainer, having on its extremity the working barrel F, which is held 35 in place at its lower end by a conical sleeve R, conveniently of rubber, to which is attached a metal ring J, supported by a collar I, riveted or otherwise secured near the end of the suction-pipe. Adjacent to this sleeve R the 40 suction-pipe end is inturned to form a seat with which coacts a foot or check valve K, and above this operates a valved piston E, carried by a working rod D.

Extending upwardly from the rod D is a 45 piston-rod C, passing through a stuffing-box q in a bed-plate B and connected with the piston of what is here shown as a steam-cylinder A, but which evidently might instead be any 50 suitable source of motive power, such as an electric, compressed-air, gas, or wind motor.

Upon the upper end of the casing H is a T-fitting l, and from this projects a nipple h, flanged at its upper end. Upon the adjacent end of the suction-pipe is a flange g, which extends over and rests upon the casing- 55 flange and serves to support the suction-pipe in place, at the same time furnishing the casing with an air-tight closure. Resting upon the flange g is a T-fitting M, flanged at f and coacting with the under side of the bed- 60 plate.

From the lateral outlet of the T extends a discharge-pipe o, in which is a check-valve P, provided with the usual air-chamber Q, it being connected by short horizontal sections 65 or nipples N and R, a vertical section V, and an elbow U with a T W, one horizontal branch of which furnishes the exit of the discharge-line, which would contain the usual means for shutting off the supply, while from the 70 other nipples, X, Y, and Y', in which is a gate or other valve Z, connects with the side outlet of the casing-T l. Into the section Y' of the connecting-pipe opens an inlet-pipe y, while from the under side of the same section 75 opens a drip or outlet pipe m. In both of these pipes may be closures or cocks n.

Into the discharge-pipe beyond the check-valve may be connected a pressure-gage T by a pipe s and into the casing a vacuum-gage K 80 by a pipe J'.

In operation the rod D and its piston E will be reciprocated at the desired speed by the connected motor, causing the foot-valve to raise and lower, drawing up water through 85 the foot-valve, and forcing it into the discharge-pipe through the check-valve, which prevents the return of the fluid. Owing to the air-tight closure between the casing and the suction-pipe, a partial vacuum will be produced therein upon the raising of the piston, which results in a greater draft of water 90 through the strainer from the surrounding soil than if the casing were open at the top and the pump operating upon water under 95 atmospheric pressure.

If the strainer becomes clogged, by opening the valve Z water may be forced back into the casing and out through the strainer- 100 openings, thus clearing it. The check-valve

P prevents the flow of water back through the line o. The pressure for this flow of water is gotten from the main discharge-line from elevated tank or through pumps connected thereto, or instead air, steam, or any fluid under pressure may be introduced through the pipe-line Y' through an independently-connecting pipe-line y.

If it is desired to learn whether there is any leakage of water from the discharge-pipe into the casing through the valve Z, it is only necessary to open the cock in the outlet-pipe m, which will show a flow therethrough should leakage exist.

15 The gages K and T permit the vacuum in the casing and the pressure in the discharge-pipe to be read at will.

It will be obvious that a considerable increase in efficiency will result from the production of the vacuum within the casing and that it will also avoid the waste of power in pumping air, as is liable to occur when the well is open at the top. Moreover, the ready and effective means of keeping the casing free 25 also adds to the pump efficiency.

Having thus described my invention, I claim as new and desire to secure by Letters Patent—

1. The combination with a well-casing having at its top an air-tight closure and communicating at its lower end with the surrounding soil, of a suction-pipe extending into the casing, and pump mechanism associated with the suction-pipe.

2. The combination with a well-casing having a perforated end and furnishing an extended chamber above the perforated portion, of a suction-pipe therein, a piston operating in the suction-pipe, and means for creating a partial vacuum in the casing upon the upward 35 movement of the suction-pipe.

3. The combination with a well-casing having a perforated end and furnishing an extended chamber above the perforated portion, of a suction-pipe extending through said cas-

ing, means for closing the top of the casing 45 against the entrance of air, a discharge-pipe leading from the upper end of the suction-pipe, check-valves in the lower end of the suction-pipe and in the discharge-pipe, and a valved piston operating in the suction-pipe. 50

4. The combination with a well-casing communicating at its lower end with the surrounding soil, of a suction-pipe therein, a piston operating in the suction-pipe, means for creating a partial vacuum in the casing upon the 55 upward movement of the piston, and a vacuum-gage connected with the casing.

5. The combination with a well-casing closed at the top, of a suction-pipe entering the casing through the closed top, and an independent pipe leading into the casing. 60

6. The combination with a well-casing closed at the top, of a suction-pipe entering the casing through the closed top, and a pipe connecting the casing and the suction-pipe. 65

7. The combination with a well-casing closed at the top, of a suction-pipe entering the casing through the closed top, a pipe connecting the casing and the suction-pipe, and a valve in the connecting-pipe. 70

8. The combination with a well-casing closed at the top, of a suction-pipe entering the casing through the closed top, a pipe connecting the casing and the suction-pipe, and a pipe opening from the connecting-pipe. 75

9. The combination with a well-casing closed at the top, of a suction-pipe entering the casing through the closed top, a pipe connecting the casing and the suction-pipe, and independent inlet and outlet pipes opening 80 into the connecting-pipe.

In witness whereof I have signed my name to this specification in the presence of two subscribing witnesses.

HORACE W. CLARK.
